CLAIM

The ornamental design for a notebook computer with multiple displays, as shown and described.

DESCRIPTION

FIG. 1 is a front view of a notebook computer with multiple displays showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view thereof with the side displays overlapping with the middle display;

FIG. 8 is a rear view thereof with the side displays overlapping with the middle display;

FIG. 9 is a left side view thereof with the side displays overlapping with the middle display;

FIG. 10 is a right side view thereof with the side displays overlapping with the middle display;

FIG. 11 is a top view thereof with the side displays overlapping with the middle display;

FIG. 12 is a bottom view thereof with the side displays overlapping with the middle display;

FIG. 13 is a front view thereof with the folded displays overlapping with the keyboard;

FIG. 14 is a rear view thereof with the folded displays overlapping with the keyboard;

FIG. 15 is a left side view thereof with the folded displays overlapping with the keyboard;

FIG. 16 is a right side view thereof with the folded displays overlapping with the keyboard;

(Continued)

FIG. 17 is a top view thereof with the folded displays overlapping with the keyboard; and, FIG. 18 is a bottom view thereof with the folded displays overlapping with the keyboard.

The dashed broken lines illustrate portions of the notebook computer with multiple displays and form no part of the claimed design.
